UNITED STATES PATENT OFFICE.

ZENAS A. CURTIS, OF DENVER, COLORADO.

VEHICLE-SHIFTING MECHANISM.

1,249,598.

Specification of Letters Patent. Patented Dec. 11, 1917.

Application filed August 2, 1916. Serial No. 112,781.

To all whom it may concern:

Be it known that I, ZENAS A. CURTIS, a citizen of the United States, residing at Denver, in the county of Denver and State of Colorado, have invented a new and useful Vehicle-Shifting Mechanism, of which the following is a specification.

This invention relates to mechanism especially designed for pulling automobiles and other vehicles out of positions where they are stalled, one of the objects of the invention being to provide mechanism of this character which is simple and compact in construction, can be readily stored in a motor vehicle or the like, and can be readily set up at any point, the mechanism being so arranged that it can be easily operated to drag vehicles out of mud holes, up embankments, etc.

20 A further object is to provide mechanism of this character in which the haul line can be quickly paid out while the mechanism is being set up.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made within the scope of what is claimed, without departing from the spirit of the invention.

In the accompanying drawings the preferred form of the invention has been shown.

In said drawings:—

Figure 1 is a plan view of the apparatus.

Fig. 2 is a side elevation of the operating mechanism, parts being shown in section.

40 Referring to the figures by characters of reference 1 designates a base plate of any suitable proportions and along the center of the top face of this plate is secured a strip 2 forming the base of an upstanding frame.

45 This strip has spaced circular openings 3 and 4, the bottoms of the openings being closed by the base plate 1. An end frame or yoke 5 extends upwardly from and is secured to one end portion of the base plate 50 and secured upon the center of this upstanding yoke is a top bar 6 one end portion of which is bent downwardly as at 7 and is secured to the corresponding end of the strip 2. This bar 6 is provided with spaced circular openings 8 and 9 respectively, said

openings being arranged directly over the openings 3 and 4.

Journalized within the alining openings 3 and 8 is a shaft 10 the lower end of which is designed to bear against the plate 1 while the upper end extends upwardly beyond the bar 6 and extends through a sleeve 11 which rests upon the bar 6 and is secured to the shaft 10 in any suitable manner, as by means of a pin 12. Formed integral with the sleeve 11 is a ratchet wheel 13 which rests upon the bar 6 and is normally engaged by a pawl 14 which can, if desired, be spring pressed, as will be obvious. Sleeve 11 is angular in cross section and is adapted to be detachably engaged by an actuating lever or crank 15.

Loosely mounted on shaft 10 is a drum 16 integral with a gear 17 which is provided at one end of the drum. A disk 18 is mounted on the other end of the drum and secured to the shaft 10 and above this disk is a small drive gear 19. Gear 17 is preferably formed with a keyhole slot 20 for the reception of the knotted end portion of a cable 21.

Mounted for rotation within the opening 4 is an eccentric 21' formed integral with one end portion of a shaft 22, the other end of the shaft being extended into an eccentric 23 which is mounted for rotation within the opening 9. A large gear 24 is adapted under certain conditions to mesh with gear 19 and this gear 24 is secured to or formed with a sleeve 25 which is mounted for rotation on the shaft 22. Another small gear 26 is secured to said sleeve 25 or formed therewith and is adapted to mesh with the gear 17.

Secured to one end of the shaft 22 is a lever 27 having a spring finger 28 extending therefrom. This finger is adapted to engage either of two studs 29 and 30 extending upwardly from the bar 6. When the finger 28 is in engagement with the stud 29, shaft 22 and the eccentrics 21' and 23 are held against rotation while the gear 24 is held in mesh with gear 19 and gear 26 is held in mesh with gear 17. However, by springing finger 28 out of engagement with stud 29 and placing it in engagement with stud 30, this one-half rotation of the shaft 22 will result in a corresponding rotation of the two eccentrics which will move the gears 24 and 26 out of engagement with the respective gears 19 and 17. Consequently the drum 16 will be able to rotate freely while the cable 21 is being unwound therefrom.

Openings 31 are formed in the plate 1 at the sides of the yoke or upstanding frame 5 and an additional opening 32 may be formed in the opposite end of the plate and in the 5 end of the strip 2.

It is designed to provide stakes preferably of metal and which have been indicated at 33 for insertion through the openings 31 and 32 and which are adapted to be driven 10 into the ground. An additional stake preferably formed of a length of T-rail 34 and provided with a plate 35 forming retaining wings, is likewise provided. A chain 36 is extended from this stake and is adapted to 15 be placed in engagement with one of the stakes 33.

When it is desired to use the apparatus for the purpose of moving a vehicle out of any position in which it may be stalled, the 20 apparatus is placed on the ground at a point beyond the vehicle and is fastened in place by driving the stakes 33 into the ground. The shaft 25 is rotated so as to shift the eccentrics thereon and move the 25 gears 24 and 26 out of mesh with the gears 19 and 17. Consequently cable 21 can be paid out rapidly and attached to the vehicle. Shaft 22 is then again rotated to move the 30 gears into mesh after which crank arm 15 is operated and will cause power to be transmitted from gear 19 to gear 24 and from

gear 26 to gear 17. This will result in a slow winding of the cable upon the drum 16. The mechanism is such, however, that considerable power is thus obtained with the 35 result that a vehicle can be easily shifted.

It will be seen that the apparatus is very durable, efficient and, by reason of its compact construction, can be easily carried in an ordinary vehicle without occupying an excessive amount of space. 40

What is claimed is:—

A vehicle shifting mechanism, comprising a frame, a shaft journaled in the frame, a drum loosely mounted on the shaft, a second shaft eccentrically journaled in the frame, a hollow shaft turning on the eccentric shaft, gearing between the hollow shaft and the drum, gearing between the hollow shaft and the first shaft, means for rotating 50 the first shaft, a resilient finger on the eccentric shaft for revolving the same, and studs on the frame and selectively engaged by the finger to lock the eccentric shaft in gear engaged or disengaged position. 55

In testimony that I claim the foregoing as my own, I have hereto affixed my signature in the presence of two witnesses.

ZENAS A. CURTIS.
